UNITED STATES PATENT OFFICE.

IVAR LUNDGAARD, OF ROCHESTER, NEW YORK.

GAS-BURNER.

1,340,902.

Specification of Letters Patent. Patented May 25, 1920.

Application filed July 31, 1918. Serial No. 247,689.

To all whom it may concern:

Be it known that I, IVAR LUNDGAARD, a citizen of the United States, residing at Rochester, in the county of Monroe and State of New York, have invented certain new and useful Improvements in Gas-Burners; and I do hereby declare the following to be a full, clear, and exact description of the invention, such as will enable others skilled in the art to which it appertains to make and use the same.

This invention relates to burners of the kind in which a blast or current of air acts to induce the gas and produce a mixture suitable for complete combustion.

The general object of the present invention is to produce a burner, of simple construction, in which air and gas are thoroughly and uniformly mixed and in which the necessity for an extended mixing-chamber and a guard or grating is eliminated. A further object of the invention is to produce a burner which will operate effectively with an air-blast at a substantially lower pressure than that which has heretofore been necessary.

In the burner of the present invention air is forced through an annular passage which flares or increases in cross-sectional area toward its discharge-end, and the gas is discharged into the stream of air at a zone where the air-stream is constricted in the narrow part of the passage, so that the gas is sucked into the air-stream in a volume proportioned approximately to the volume of air. Preferably the mixing-passage has a form such as to produce what is known as the Venturi effect. By the use of a comparatively constricted gas-orifice, or a series of such orifices, arranged in annular form, it is possible to obtain a homogeneous mixture of gas and air within a very short distance from the point of gas-admission, thus dispensing with the necessity of an extended mixing-chamber and of a perforated guard or grating.

In the accompanying drawings Figure 1. is a longitudinal sectional view of a gas-burner embodying the present invention, and Figs. 2, 3 and 4 are similar views of modified forms of the invention.

The illustrated embodiment of the invention comprises a cylindrical outer tube 5 which provides the mixing-chamber and constitutes also the air-tube, being fed with

air at a suitable pressure. Within the air-tube 5 is a head 6 which is supported concentrically with the tube in any convenient manner. The head is tapered toward each end, so that the annular passage between the head and the air-tube has a longitudinal section resembling that of a Venturi tube, comprising a contracting portion 7 and an expanding or flaring portion 8.

The gas is introduced into the air-stream 65 at the most restricted zone of the passage just described, through an annular series of small perforations 9 in the head 6. These perforations discharge from a central gas-chamber 10 in the head, and this chamber 70 is fed with gas through a pipe 11 arranged concentrically within the air pipe 5. As shown in the drawings the gas-pipe constitutes the support for the head 6, the gas-pipe and the air-tube being maintained in 75 concentric arrangement by any convenient means (not shown).

The air, in its movement through the passage 7-8, induces a flow of gas, through the perforations 9, which varies with the 80 volume of air which passes, and owing to the distribution of the gas through a considerable number of such perforations, the gas is mingled with the air while passing through the short space between the perforations 9 and the discharge-end of the air-tube, so that an intimate mixture is produced without the necessity of an extended mixing-chamber.

An important feature of the present 90 burner resides in the fact that the elongated mixing-tube or chamber usually employed in gas-burners is dispensed with, as well as the grating or gauze usually necessary to prevent back-firing in such mixing-tubes. 95 In the present burner, therefore, it is necessary to maintain a comparatively high velocity in the combustible mixture while it is passing from the gas-orifices 9 to the open end of the air-tube, in order that the flame 100 may not, under normal conditions, strike back too far into the space within the air-tube. For this reason the forward part of the head 6 is tapered at only a slight angle, such that, if the head were continued to 105 form a complete cone, the apex would lie a considerable distance in front of the forward extremity of the air-tube. If so continued, however the head would be subjected to the heating effect of the flame to a degree 110

which would be inadmissible. Accordingly, the head is cut off or truncated at a point within the air-tube where it is nearly removed from contact with the flame.

- 5 It has been found that the air-pressure required in this arrangement is comparatively small and however much this pressure be reduced, no harm will result from the striking back of the flame, even though the 10 flame pass back fully to the gas-orifices 9. In such case the resumption of full air-pressure will cause the flame to return to its normal position.

Owing to the intimate mixture of the air 15 and the gas the combustion occurs at and partly within the mixing-chamber, so that it is usually desirable to protect the head or the air tube, or both, from the heat of the flame. In Fig. 2 the air-tube is shown as 20 provided with an annular water-jacket 12 provided with inlet and outlet passages 13 and 14 through which a current of water may be passed. Fig. 3 shows a means for 25 protecting the head 6, this means having the form of a cap 15 of refractory material such as fire-clay, secured to the head by means of a cross-pin 16. In Fig. 4 the head is similarly protected, and the air-tube 5 is 30 provided with a tip 17 of refractory material. These protective devices are useful particularly where the burner is to be regulated through wide degrees, so that combustion may sometimes occur to a considerable

extent within the discharge-end of the air-tube.

Although the gas is, in the illustrated 35 burners, introduced through a series of distinct narrow orifices, this detail is adopted merely for convenience in construction, the essential feature being the introduction of 40 the gas substantially throughout the constricted zone of the mixing-passage.

The invention is not limited to the embodiment thereof hereinbefore described and illustrated in the accompanying drawings, but it may be embodied in various 45 other forms within the scope of the following claims.

The invention claimed is:

1. A gas-burner comprising: an air-tube 50 serving, at its forward open end, as a mixing-chamber; a head, concentric with the air-tube near said end and provided with annularly arranged gas-outlet openings; and means for supplying gas to said head; the head being substantially of greatest diameter at said openings and tapering forwardly therefrom substantially in the form of a cone, of which the apex is located a substantial distance beyond the extremity 60 of the air-tube, but which is truncated within said extremity.

2. A gas-burner, as in claim 1, in which the truncated conical end of the head has a surface of refractory material.

IVAR LUNDGAARD.
